UNITED STATES PATENT OFFICE.

ABRAHAM FELLDIN, OF AUBURN, NEW YORK.

TUNING-PIN AND ADJUSTING-SCREW FOR PIANOS.

SPECIFICATION forming part of Letters Patent No. 550,366, dated November 26, 1895.

Application filed June 29, 1894. Serial No. 516,048. (No model.)

To all whom it may concern:

Be it known that I, ABRAHAM FELLDIN, a citizen of the United States, and a resident of Auburn, in the county of Cayuga and

5 State of New York, have invented certain new and useful Improvements in Tuning-Pins and Adjusting-Screws for Pianos and other Stringed Instruments, of which the following is a specification.

10 My invention relates to means for stretching and tuning the strings of pianos and other stringed instruments; and it consists of the improved construction of the adjusting-screws for facilitating the connection of the 15 same with the strings, all as hereinafter described and claimed, reference being made to the accompanying drawings, in which—

Figure 1 is a transverse section of the string-frame, sounding-board, and bridge of a piano, 20 showing my improvements in the tuning and adjusting pins. Fig. 2 is a detail showing one of the adjusting-screws, partly in side elevation and partly in sectional elevation, also showing part of a string and a ball for connecting the string and the screw.

25 In the metallic side bar *a* of the string-frame in which the tuning-pins *b* are set I make the taper holes *c* for said pins in an acute angle to the strings *d*, said angle being such that the stress of the strings on the 30 pins keeps them tight in the taper holes or sockets, and they do not work slack, and thus keep the strings in tune much longer or continuously without any other means of fastening them, and on the pins thus angularly arranged I coil the strings upwardly from where the ends are secured in the holes *m*, so that the stress of the strings draws the coils down close on each other in a compact condition 35 more favorable to the keeping of the strings in tune than when the strings are wound from above downward, in which condition the coils are liable to shift on the pins and alter the tune.

40 To facilitate boring the holes in inclined relation to the strings, the bar *a* is made with surface planes *e*, where the holes are to be bored at right angles to the lines of the holes, whereby the drill-points are relieved of the 45 side thrusts to which they would be subject

at starting in a bar whose surface is parallel with its plane; but I make no claim to this device nor to that described in the preceding paragraph.

For connecting the adjusting-screws *f* with 55 the strings *d* in a simple way, so that they may turn freely in the bar *g* for regulating the tension of the strings and so as to afford easy connection of said screws with the strings, I make the screws with a concave socket *h* in 60 the end of each one and provide a perforated ball or bead *i* for each string, preferably of the same radius as that of the socket, which, being strung on the string and seated in the cavity of a screw, forms a simple bearing, allowing the screw to turn freely for adjusting the string and being adapted for fixing in place in the cavity of the screw more readily than a notched pin fitted to a bored socket in the end of the screw, which has to be carefully directed to enter the end of the pin in the notch, whereas the ball or bead will keep its position on the string and will enter the socket more readily and with much less care than the pin will.

75 The part *j* indicates the opposing bar of the string-frame, *k* the sounding-board, and *l* the bridge, which will be in any ordinary or approved arrangement.

I am aware that taper pins considerably enlarged above the portion on which the strings are wound and milled in the taper portion have been used in taper holes bored at right angles to the pull of the strings, as in the 80 patent to Carnes, No. 352,395; but these do not hold well, and they have to be frequently 85 tuned.

I am also aware that taper pins have been fitted at a slightly-acute angle to the pull of the strings in taper holes through a thin pin-holding plate with adjusting-nuts on the under side of the plate to hold the pins, as in the 90 patent to Smith, No. 488,483; but this involves considerable additional expense and the trouble of adjusting the nuts every time the 95 strings are tuned, and I am also aware that a taper-tuning "key" is used in a hole at right angles to the pull of the string with an adjusting-screw under the plate in addition to the pin inserted in a hole formed at an ob- 100

tuse angle to the pull of the string, as in the Patent No. 420,914, and I make no claim to the devices of these several patents.

I claim—

- 5 The combination with the strings of a piano or other musical instrument, of tension adjusting screws having sockets in the ends to be connected with the strings, and perforated ball or bead bearings strung on the strings 10 for connecting with said sockets, said tension

screws being supported in the usual tension screw supporting bar substantially as described.

Signed at Auburn, in the county of Cayuga and State of New York, this 28th day of May, 15 A. D. 1894.

ABRAHAM FELLDIN.
